UNITED STATES PATENT OFFICE

2,480,903

TUBULAR HEATER TERMINAL SEAL

Allan P. Charbonneau, Wauwatosa, Wis., assignor
to Cutler-Hammer, Inc., Milwaukee, Wis., a
corporation of Delaware

Application June 25, 1947, Serial No. 757,045

6 Claims. (Cl. 201—63)

1

This invention relates to electric heaters and more particularly to an improved method of and means for sealing the terminals of heaters having tubular enclosing sheaths.

Heretofore production of fluid impervious terminal seals for electric heaters of the sheathed type has been rendered difficult due to formation of gases within the heater during the process of sealing, such gases tending to escape through the sealing materials before solidification, thereby causing bubbles and pin holes which render the seals imperfect. Methods and means have been proposed to overcome the difficulty by sealing in progressive steps which provide for reducing the gas pressure prior to the final step but such expedient involves complications and its success is questionable.

It is a primary object of the present invention to provide for sealing under conditions such that little or no gas is produced within the heater during the process of sealing.

Another object is to provide for making a highly satisfactory terminal seal in a simpler and more expeditious manner.

Another object is to provide for sealing purposes elements which may be readily coordinated and converted into a strong seal impervious to moisture by localized heating.

Other objects and advantages of the invention will hereinafter appear.

The accompanying drawings illustrate an embodiment of the invention which will now be described; it being understood that the embodiment is susceptible of various modifications without departing from the scope of the appended claims.

In the drawings:

Figure 1 is a view in longitudinal section of a portion of a tubular type heater prior to application of a terminal seal,

Fig. 2 is like Fig. 1 but showing the heater at one stage during the application of a terminal seal, and showing in broken lines parts of the processing apparatus which may be employed, and

Fig. 3 is an enlarged view of the terminal seal in a completed state.

Referring to Fig. 1, it shows a tubular type electric heater comprising a helical resistor 6 which is embedded in a compacted mass of refractory insulating material 7 and incased by a tubular metal sheath 8 of circular form in cross section. The resistor 6 is connected in any preferred manner to a terminal member 9 which extends outwardly of the sheath 8. The sheath adjacent its 55

2

end is unfilled and provides a recess 10 to receive the component elements of the terminal seal.

The insulating material 7 may be of any of the well-known types of refractory materials, such as magnesium oxide and it is assumed that the heater has been completely worked as by swaging to the desired cross-sectional dimensions and also formed in the desired configuration. It is further assumed that the heater has been subjected to an annealing treatment to remove the stresses incurred during working and to remove the greater percentage of the moisture entrained in the insulating material 7. It is also assumed that in preparation of the application of the improved terminal seal the inner surface of sheath 8 surrounding recess 10 has been suitably cleaned.

Referring to Fig. 2 a quantity of glass frit 11 preferably in powdered form is placed in recess 10. A glass tube 12 of circular cross section is then partially inserted in recess 10 so as to have contact with and to extend into the frit 11. Tube 12 is preferably greater in length than the recess 10, and preferably has an appreciable but small clearance from the sheath 8. A metal bushing 13 preferably of steel is slipped onto the terminal 9 and into the glass tube 12, said bushing having appreciable but small clearance from terminal 9 and glass tube 12.

Bushing 13 preferably is provided with an enlarged end portion 16 which is adapted to overlie the outer end of tube 12 and preferably the bushing 13 exclusive of portion 16 is of the same length as tube 12.

The aforementioned clearances provided between sheath 8, tube 12, bushing 13 and the terminal 9 are desirable for sealing purposes as will later appear. Preferably the tube 12 and the bushing 13 are formed of materials having approximately the same coefficients of expansion as the material forming sheath 8 to insure maintenance of the aforementioned clearance openings during heating of the terminal end of the heater for sealing.

After the frit 11, tube 12 and bushing 13 have been assembled within recess 10 as aforescribed, that portion of sheath 8 coextensive with the recess 10 is subjected to a localized heating to cause fusion and/or liquification of the frit 11 and to render the tube 12 plastic, the remaining portion 50 of the heater being maintained cool and thereby avoiding generation of troublesome gases within the body of the heater.

Preferably, the localized heating is obtained by placing the aforementioned end portion of the heater in a high frequency induced electromag-

netic field (see broken line showing of excited coil) while supporting the heater vertically, with its terminal end uppermost, by means of a fluid cooled clamp or support (see broken line showing of clamp) immediately adjacent the portion subjected to the field. The frequency of the field to be used can vary between 25,000 and 400,000 cycles per second; depending upon the thickness of sheath 8, the mass of bushing 13, etc. 200,000 cycles per second has been found to be a suitable average working value. It has been found that if the aforescribed assembled elements are subjected to the latter frequency for a matter of a few seconds, this is sufficient to cause complete fusion and liquification of the frit 11 and to render tube 12 plastic.

When the heater has been thus heated, pressure is exerted inwardly on the bushing 13 towards the bottom of recess 10 and when the outer end of tube 12 is engaged by the inner face of the enlarged end portion 16 of bushing 13 the tube 12 is moved inwardly therewith. This causes the fused frit to flow into the aforementioned clearance spaces between sheath 8, tube 12, bushing 13, and terminal 9. Then the terminal end of the heater is permitted to cool and in a matter of a few seconds the fused frit solidifies thereby affording a bond and seal between adjacent portions respectively of sheath 8, tube 12, bushing 13 and terminal 9, such bond also extending between the insulation 7 and the tube 12 and bushing 13.

Preferably, a sufficient quantity of the frit 11 in powdered form is initially introduced in the recess 10 as aforescribed to insure complete sealing throughout the perimeters and lengths of all the aforementioned clearance spaces.

The completed terminal seal which is effected by the method and means aforescribed is shown in Fig. 3. The solidified frit is shown between the inner ends of tube 12 and bushing 13, and the insulating material 7 as 11^a, between sheath 8 and tube 12 as 11^b, between tube 12 and bushing 13 as 11^c, and between bushing 13 and terminal 9 as 11^d.

As will be noted, tube 12 and bushing 13 extend beyond the end of sheath 8. The tube 12 provides a suitable electrical insulating barrier between the sheath and the bushing 13.

While the bushing 13 may be of any metallic conducting material it is preferably made of steel to insure even and rapid heating from within and without the terminal end of the heater when the latter is placed in the induction field as aforescribed. The use of a steel bushing also enhances the strength of the completed terminal seal.

Referring to the broken line showing in Fig. 2 of the processing apparatus, the high frequency heating means is depicted schematically as comprising a heating coil 20 supplied by a high frequency generator 21. Preferably the coil 20 comprises tubing for quick cooling. The clamping means depicted in Fig. 2 may be assumed to comprise two clamping blocks 23 and 24 forming an annulus to bear against the sheath and having passages 25 for circulation therethrough of cooling fluid. The two blocks are indicated as interconnected by tubing and it may be assumed that the circulating fluid enters one block and exhausts from the other. Obviously the heating means inherently tends to localize the heating of the sheath and enclosed parts and with the fluid cooled clamp it has been found that the body of the heater being sealed will remain sufficiently

cool to avoid generation of troublesome gases therein.

Whereas the sheath 8 has been described as being circular in cross sectional form, it will be apparent that a terminal seal of the aforementioned improved type may be applied to sheathed heaters of whatever cross sectional form by suitably forming the tube 12 and the bushing 13 to conform to the particular cross sectional form of the heater sheath.

Also localized heating may be effected in any other desired way, high frequency heating being preferred because of its rapidity.

What I claim as new and desire to secure by Letters Patent is:

1. The method of sealing the terminal end of an electric heater wherein a resistor enclosed in an open end tubular sheath is embedded in insulation terminating at a distance from the end of the sheath to leave the sheath with an open end recess, and wherein the resistor has a terminal portion projecting through such recess to a point beyond the sheath and such terminal portion is loosely surrounded by a metal bushing which in turn is loosely surrounded by an insulating tube to loosely fit within the end recess in the sheath, which comprises placing a quantity of glass frit in the end recess in the sheath, inserting into the end recess portions of the insulating tube and the metal bushing to contact the glass frit, heating locally and quickly the end of the sheath to fuse the glass frit, and pressing into the fused glass frit the insulating tube and the metal bushing to force the fused frit into the spaces between adjacent surfaces of the sheath, the insulating tube, the metal bushing and the resistor terminal portion to seal such spaces.

2. The method of sealing the terminal end of an electric heater wherein a resistor enclosed in an open end tubular sheath is embedded in insulation terminating at a distance from the end of the sheath to leave the sheath with an open end recess, and wherein the resistor has a terminal portion projecting through such recess to a point beyond the sheath and such terminal portion is loosely surrounded by a metal bushing which in turn is loosely surrounded by an insulating tube to loosely fit within the end recess in the sheath, which comprises subjecting the sheath adjacent the point of termination of the insulation within the sheath to the influence of a cooling medium, placing a quantity of glass frit in the end recess in the sheath, inserting into the end recess portions of the insulating tube and the metal bushing to contact the glass frit, heating locally and quickly the end of the sheath to fuse the glass frit and pressing into the fused frit the insulating tube and the metal bushing to force the fused frit into the spaces between adjacent surfaces of the sheath, the insulating tube, the metal bushing and the resistor terminal portion to seal such spaces.

3. The method of sealing the terminal end of an electric heater wherein a resistor enclosed in an open end tubular sheath is embedded in insulation terminating at a distance from the end of the sheath to leave the sheath with an open end recess, and wherein the resistor has a terminal portion projecting through such recess to a point beyond the sheath and such terminal portion is loosely surrounded by a metal bushing which in turn is loosely surrounded by an insulating tube to loosely fit within the end recess in the sheath, which comprises subjecting the sheath adjacent the point of termination of the

insulation within the sheath to the influence of a cooling medium, placing a quantity of glass frit in the end recess in the sheath, inserting into the end recess portions of the insulating tube and the metal bushing to contact the glass frit, subjecting locally the end of the sheath to high frequency heating to fuse the glass frit and pressing into the fused frit the insulating tube and the metal bushing to force the fused frit into the spaces between adjacent surfaces of the sheath, the insulating tube, the metal bushing and the resistor terminal portion to seal such spaces.

4. The method of sealing the terminal end of an electric heater wherein a resistor enclosed in an open end tubular sheath is embedded in insulation terminating at a distance from the end of the sheath to leave the sheath with an open end recess, and wherein the resistor has a terminal portion projecting through such recess to a point beyond the sheath and such terminal portion is loosely surrounded by a steel bushing which in turn is loosely surrounded by a glass tube to loosely fit within the end recess in the sheath, which comprises subjecting the sheath adjacent the point of termination of the insulation within the sheath to the influence of a cooling medium, placing a quantity of glass frit in the end recess in the sheath, inserting into the end recess portions of the glass tube and the steel bushing to contact the glass frit, subjecting locally the end of the sheath to high frequency heating to fuse the glass frit and pressing into the fused frit the glass tube and steel bushing to force the fused frit into the spaces between adjacent surfaces of the sheath, the glass tube, the steel bushing and the resistor terminal portion to seal such spaces.

5. The combination with a tubular heater comprising a resistor having a terminal portion, an open end tubular sheath surrounding said resistor and also its terminal portion in part, and insulation in said sheath retaining said resistor in spaced relation to said sheath, said insulation terminating at a distance from the end of said sheath leaving said sheath with an open end recess through which said terminal portion projects, of a seal for the terminal end of said heater constructed for sealing by brief heating localized thereto thereby to avoid generation of gases within the insulation containing portion of said heater and furthermore constructed for sealing

at all essential points as one operation, said seal comprising a metal bushing loosely surrounding the terminal portion of said resistor, an insulating tube loosely surrounding said bushing and having clearance from said sheath, and sealing material, such seal components occupying the open end recess in said sheath and said sealing material comprising glass frit heated in situ and filling the spaces between said sheath, said insulating tube, said bushing and said terminal portion of said resistor.

6. The combination with a tubular heater comprising a resistor having a terminal portion, an open end tubular sheath surrounding said resistor and also its terminal portion in part, and insulation in said sheath retaining said resistor in spaced relation to said sheath, said insulation terminating at distance from end of said sheath leaving said sheath with an open end recess through which said terminal portion projects, of a seal for the terminal end of said heater constructed for sealing by brief heating localized thereto thereby to avoid generation of gases within the insulation containing portion of said heater and furthermore constructed for sealing at all essential points as one operation, said seal comprising a steel bushing loosely surrounding the terminal portion of said resistor, a glass tube loosely surrounding said bushing and having clearance from said sheath, and sealing material, such seal components occupying the open end recess in said sheath and said sealing material comprising glass frit heated in situ and filling the spaces between said sheath, said glass tube, said bushing and said terminal portion of said resistor.
